UNITED STATES PATENT OFFICE.

HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 920,600.

Specification of Letters Patent.

Patented May 4, 1909.

Application filed June 27, 1905. Serial No. 267,178.

To all whom it may concern:

Be it known that I, HENRY W. MERRITT, citizen of the United States, and resident of Syracuse, in the county of Onondaga and State of New York, have invented certain new and useful Improvements in Type-Writing Machines, of which the following is a specification.

My invention relates to typewriting machines, and more particularly to the spacing key and the associated parts which control the escapement mechanism.

The object of my invention is to produce a simple and efficient mechanism of the character specified and one in which a minute adjustment may be effected between the spacing key and the escapement mechanism.

To the above and other ends, which will hereinafter appear, my invention consists in the features of construction, arrangements of parts and combinations of devices to be hereinafter described and claimed.

In the accompanying drawings wherein like reference characters indicate corresponding parts in the different views, Figure 1 is a vertical front to rear sectional view of one form of typewriting machine showing my invention applied thereto, and Fig. 2 is a detailed top plan view of a portion 30 of the machine with parts broken away to better illustrate other features of the device.

I have shown my invention applied to a Monarch typewriting machine, though it should be understood that the invention may be applied to various other forms of typewriting machines.

In the drawings, 1 indicates the base of the machine from which corner posts 2 project, the corner posts supporting a top plate 3. A suitable carriage (not shown) travels from side to side of the machine and carries a platen 4 diagrammatically shown in Fig. 1. Key levers 5 are fulcrumed against a fulcrum plate 6, which is secured to the base of one of the machines; the forward ends of the key levers are provided with the usual finger keys 7, and each key lever has an upright sub-lever 8 pivoted thereto at 9 and the lower end of each sub-lever is bifurcated at 10 for the reception of a fulcrum rod 11, which extends transversely beneath the key levers and is secured at its ends to the base of the machine. The upper end of each sub-lever 8 is pivoted at 12 to a for-

wardly extending link 13 which in turn is pivoted at its forward end 14 to a type bar 15. The various type bars are pivoted on a pivot wire 16 supported on a type bar segment 17, and work in slots 18 in a segment and are segmentally arranged and adapted to swing upwardly and rearwardly to the printing point. Type bar restoring springs 19 are each connected at one end to a hook 20 and at the other end to a link 21, which in turn is pivoted to the associated type bar. 25

Extending transversely beneath the various key levers 5 is a universal bar 22 that is connected at its ends to lever-like arms 23, which, with the universal bar, form a yoke. The lever-like arms are rigidly secured to a rock shaft 24 which extends between depending bracket plates 24^a, the latter being secured to the base of the machine and carrying bearing screws 24^b on which the shaft 24 turns. The forward ends of the lever-like arms 23 extend over and are adapted to cooperate with adjustable set screws or devices 25 and are operatively connected to the spacing bar of the machine, as will hereinafter more clearly appear. Projecting rearwardly from the rock shaft 24 is a rigidly connected arm 26 to which an upright link 27 is pivoted at 28. The upper end of the link is pivoted at 29 to a forwardly projecting arm 30 of a dog rocker which has a rock shaft from which an upwardly projecting arm 32 extends, the arm 32 carrying the usual feed-dog 33 which co-operates with a feed rack 34 diagrammatically shown in Fig. 1; it being understood that the rack 34 is operatively connected with the carriage. An arm 35 extends forwardly from the rock shaft 24 and has an upwardly tending seat 36 that receives one end of a coiled restoring spring 37, the upper end of said spring being received on a similar seat projecting from a bracket 38 secured to a cross bar 38^a on the base of the machine. Thus it will be seen that the parts 22, 23, 24, 26 and 35 constitute a frame that is operatively connected to the escapement and that the forwardly projecting ends of the lever-like arms 23 of said frame co-act with the screws 25. The spring 37 tends to restore the universal bar and the parts connected thereto to their normal positions, as represented in Fig. 1. A spacing bar 39 is connected at its ends to the forward ends of sheet metal spacing levers 40

which are united near the rear end portions by a transversely extending bracing strip 41. The levers 40 are pivoted on a pivot rod 42 which extends from side to side of the machine and is secured at its ends to the base 1. The levers 40 extend beyond the pivoted rod 42 and have suitable bearings for the set screws 25, hereinbefore described, and in the present instance the levers are shown as bent inwardly at 43 and are perforated and tapped to receive the set screws 25 which extend therethrough, and the upper ends of the screws are adapted to bear against the forward ends of the lever-like arms 23 which are connected to the universal bar, thus transmitting motion to the universal bar, the rock shaft 24, the rearwardly extending arm 26, link 27 and the dog rocker.

From the foregoing description it will be understood that the screws 25 constitute individual adjusting means by which any inaccuracies in the spacing bar frame or the universal bar frame may be compensated for, and by which a uniform extent of dip may be given to the space key irrespective of any variations in the throw of the dog rocker. Furthermore, it will be observed that the adjustment of the screws to control the dip of the space key may be effected without affecting the universal bar or the escapement. The adjusting screws likewise afford individual adjusting means between each spacing key lever and each lever-like arm 23 of the universal bar for causing proper engagement between the two.

The spacing bar, levers 40 and the strengthening or connecting strip 41 form a four-sided substantially rectangular frame which is restored to its normal position by springs 44, each of which is bent inwardly at its forward end, as indicated at 45, and bears upon the upper side of a spacing lever 40 near the inwardly bent portion 45 so as to depress the rear end of the frame and thus elevate the forward end thereof, and the spacing bar 39. The rear end of each of the springs 44 is rigidly secured to a fixed portion of the machine by a screw 45.

From the foregoing description, it will be seen that I have provided simple and efficient means for effecting an adjustment between the space key and the universal bar

without affecting the normal position of the latter.

What I claim as new and desire to secure by Letters Patent, is:

1. In a typewriting machine, the combination of sheet metal levers connected at their forward ends by a space key and each having a threaded bearing at the rear end thereof and in the rear of the pivot of said lever, screws carried by and adjustable in said bearings, a universal bar, and a frame to which said bar is connected, said frame having forwardly projecting arms with which said screws are adapted to contact.

2. In a typewriting machine, the combination of sheet metal levers connected at their forward ends by a space key and each having a threaded bearing at the rear end thereof and in the rear of the pivot of said lever, a sheet metal strengthening strip which connects said levers and forms a four-sided frame with said levers and spacing key, screws carried by and adjustable in the bearings in said levers, a universal bar, and a pivoted frame to which said bar is connected, said pivoted frame having forwardly projecting arms with which said screws are adapted to contact.

3. In a typewriting machine, the combination of a universal bar, lever-like arms to which said universal bar is connected, a rock-shaft to which said lever-like arms are rigidly connected and by which the lever-like arms and universal bar are supported, escapement mechanism, connections from said rock shaft to said escapement mechanism, pivoted space key levers, a space key that connects the forward ends of said levers, a strengthening bar that unites the space key levers forward of the pivots thereof, and an adjustable screw between the rear end of each of said space key levers and the forward end of each of the lever-like arms of the universal bar.

Signed at Syracuse, in the county of Onondaga, and State of New York, this 23d day of June A. D. 1905.

HENRY W. MERRITT.
